CLAIM

The ornamental design for a shower pole caddy, as shown and described.

DESCRIPTION

FIG. 1 is a perspective view of a shower pole caddy.

FIG. 2 is a front view of the shower pole caddy of FIG. 1.

FIG. 3 is a rear view of the shower pole caddy of FIG. 1.

FIG. 4 is a left side view of the shower pole caddy of FIG. 1.

FIG. 5 is a right side view of the shower pole caddy of FIG. 1.

FIG. 6 is a top view of the shower pole caddy of FIG. 1; and, FIG. 7 is a bottom view of the shower pole caddy of FIG. 1. The dash-dash and dot-dot-dash lines are features of the shower pole caddy that form no part of the claimed design.
